ELECTRON-DISCHARGE-TUBE AMPLIFIER SYSTEM.

Application filed July 9, 1925. Serial No. 42,399.

This invention relates to three-electrode vacuum tube amplifying systems, and more particularly to tuned radio frequency amplifying systems embodying electron discharge devices or tubes; and has special reference to the provision of improved means for controlling the stabilization and the energy output or volume of such tuned radio frequency amplifying systems.

10 The principal object of my present invention comprehends the provision of a method of and means for controlling the energy output or volume of electron discharge tube amplifying systems, and for simultaneously controlling the feed-back reactions in and selectivity of the system, the present invention consisting in improvements in the method of and means for controlling energy feed-back in electron discharge devices, described 15 and claimed in my copending application Ser. No. 743,342, filed Oct. 8, 1924.

It is well known that due to the unshieldable capacity between the electrodes, and notably between the plate and grid, of an electron discharge tube, a retransfer or feed-back of energy takes place from the output or plate circuit of the tube to the input or grid circuit, which energy or power feed-back is highly objectionable, especially in 20 relay, amplifying or modulating circuits, because it gives rise to distortion of the input voltage power wave form and to incipient or sustained oscillations in the grid circuit, which oscillations interfere with efficient reception, amplification and detection of the received signals. Where a plurality of electron discharge tubes are employed in cascade, as for example in multi-stage radio frequency amplifying systems, this objectionable retransfer or feed-back of energy 25 takes place through a number of channels due to the coupling between the cascaded circuits, which may be described as adjacent and distant stage feed-back, the adjacent stage feed-back being that moving from the plate circuit of a tube to the grid circuit of such tube, and the distant stage feed-back being that moving from a grid or plate circuit of one tube back to the grid 30 circuit of a preceding tube. To produce an efficient amplifying system wherein the maximum amplification by relay action of the tube is to be obtained and wherein stability of the circuits, ease of tuning thereof and efficient tone quality are to be effected,

it is requisite to neutralize or eliminate both the adjacent and distant stage feed-backs.

To reduce and eliminate this objectionable feed-back or retransference of energy, a number of methods have heretofore been suggested or devised, and in my aforementioned copending application Ser. No. 742,342, there is described a method for neutralizing or eliminating the energy feed-back which consists in producing a transfer or feed-forward of energy from the grid circuit to the plate circuit for predeterminedly controlling the feed-back taking place from the plate circuit to the grid circuit, this being accomplished by the provision of resistance means in the plate circuit which functions to abstract energy from the grid circuit in proportion to and corresponding in variation with the energy retransfer taking place from the plate to the grid circuit 75 across the grid-plate capacity. The present invention has for its principal object improvements in this method of controlling or neutralizing feed-back reactions in amplifier circuits, and one in which the energy output 80 or volume of the system as a whole may be controlled by the means for controlling the feed-back and stabilization of the system.

Further prime objects of the present invention include the provision of tuned radio frequency amplifying systems in which the amplitude of the output energy may be controlled over a wide range of variation, as for example from one to ten thousand, without altering the filament current of the amplifier tubes; the further provision of tuned radio frequency systems in which a single control element may be employed for simultaneously controlling the amplification and the stabilization of the system; and the still 90 further provision of improvements in tuned radio frequency amplifying systems in which the damping or selectivity of cascaded circuits may be predeterminedly controlled in a simple way along with the control of the 95 energy output or amplification of the system.

To the accomplishment of the foregoing and such other objects as will hereinafter appear, my invention consists in the elements and their relation one to the other, as hereinafter particularly described and sought to be defined in the claims; reference being had to the accompanying drawings which show the preferred embodiments of my invention, in which:

Fig. 1 is a wiring diagrammatic view of a radio receiving system of the tuned radio frequency type employing two stages of radio frequency amplification and showing 5 the principles of my present invention applied thereto,

Fig. 2 is a wiring diagrammatic view of a modification of the invention,

Fig. 3 is a graphical view exemplifying 10 the principles of the invention, and

Fig. 4 is a graphical view showing the principles of the invention embodied in a modification of the control means.

Referring now more in detail to the drawings, and having particular reference first to Fig. 1 thereon, I show a radio receiving system of the tuned radio frequency type having two stages of radio frequency amplification followed by a stage of detection. 15 This system comprises a plurality of electron discharge devices a , a' and a'' , each including a cathode or filament 10, a grid or screen 11, and an anode or plate 12, the three electrodes being contained in an evacuated envelope 13. The electron discharge device a is provided with an input or grid circuit generally designated as i connected to an energy receiving circuit such as the antenna circuit n , and is provided with an 20 output or plate circuit generally designated as o which is linked by means of an inductive coupling device such as the transformer T^2 to an input or grid circuit i' associated with the electron discharge device a' . The 25 electron discharge device a' is also provided with an output or plate circuit o' which is linked by the coupling means or transformer T^3 to an input circuit i'' of the detecting 30 electron discharge device or tube a'' ; the tube a'' being provided with the output circuit 35 which may be the phone circuit o'' .

The first input circuit i may comprise the conventional tuning means such as the variocoupler T^1 having its primary p' in the antenna circuit n and its secondary s' in the 40 first grid circuit i , and a variable tuning condenser 15 in shunt with the variometer secondary s' , one side of the tuning means being connected to the grid 11 by means 45 of the conductors 16 and 17, and the other side of the tuning condenser being connected to the filament 10 by means of the conductors 18 and 19 and a fixed resistance 20. For heating the filament 10 to incandescence, to effect the electron discharge emission, there is provided the filament circuit 50 generally designated as f , which comprises the battery A , the negative terminal of which is connected to the filament by means 55 of the conductors 21 and 22 and the resistance 20, and the positive terminal of which is connected to the filament by means of the conductors 23 and 24. The output circuit o includes the battery B , the negative 60 terminal of which may be connected to the

negative terminal of the A battery by means of the conductor 25, and the positive terminal of which is connected by means of the conductors 26 and 27 to the primary p'' of the coupling transformer T^2 having the secondary s'' , the said transformer primary being 70 in turn connected to the plate 12.

For controlling or compensating for the retransference of energy or adjacent stage feed-back taking place from the output circuit o to the input circuit i of the first radio frequency tube a across the capacity coupling between the grid and plate, which may be represented in dotted line by the condenser c , I employ the resistance means described 80 and claimed in my aforesaid copending application, which comprises a high resistance R arranged in the plate circuit o and so related to the output impedance of the transformer T^2 and the filament plate impedance 85 of the tube a as to produce an abstracting or feed-forward of energy from the input circuit i at substantially the same rate as energy is fed back from the plate circuit o to the grid circuit i through the grid-plate capacity of the tube, the resistance being thus 90 effective for neutralizing the objectionable feed-back reaction taking place.

This resistance R is preferably inductance-free so that all of the available inductance 95 may be conserved for the energy transfer from the tube a to a succeeding tube, and is preferably capacity-free, so that the resistance may be kept as small as possible to minimize the decrease of plate voltage due to the voltage drop in the plate circuit, and so that a balance for all frequencies may be had. The magnitude of this resistance is preferably from 500 to 4,000 ohms, and is generally made equal to the ratio of the filament-plate impedance to the amplification 100 constant of the tube. The resistance should be high enough to effect the desired control, but should in practice be maintained at a minimum so as to prevent any appreciable 110 voltage drop across the resistance, and therefore any appreciable drop or reduction in the plate voltage.

Viewed from the standpoint of the energy 115 relations in the interlinked or coupled input and output circuits of the tube a , the insertion of the resistance R in the plate circuit has the effect of absorbing or abstracting energy from the grid circuit in proportion to and corresponding in variation with the 120 energy retransfer or feed-back that takes place from the plate circuit to the grid circuit. Viewed from the standpoint of the resistance relations of the interlinked circuits, the resistance R in the plate circuit has the 125 effect of introducing a positive resistance in the grid or input circuit i which may be made to neutralize the negative resistance of the grid circuit resulting from the feed-back of energy thereto. The abstraction of 130

energy or the energy feed-forward from the input circuit produced by the resistance in the plate circuit is 90° out of phase with the energy feed-back, but takes place in each 5 cycle so that the energy feed-back is effectively compensated for or neutralized.

The effect of the inserted resistance in the plate circuit of producing a feed-forward of energy from the input circuit to the output 10 circuit in opposition to the energy feed-back from the output to the input circuit may be explained on the theory that the feed-forward capacity current through the grid-plate capacity is in effect magnified by the 15 resistance in the plate circuit due to the said resistance producing a larger than the normal voltage on the plate which is in phase with the grid voltage, and this current is in series with the inserted plate resistance, and 20 therefore tends to abstract energy from the preceding input circuit. Thus the resistance in producing a larger inphase voltage component has the effect of producing a larger capacity current, and more particularly a 25 larger feed-forward capacity current moving from the grid to the plate; and this feed-forward of energy may be controlled by the size or magnitude of the resistance to nullify any part or the whole of the 30 energy feed-back. This theory further explains the reason why the feed-forward of energy always equalizes the feed-back of energy independent of any change in the tube characteristics or constants, this being 35 an important advantage flowing from the invention, such equalization of the feed-forward of energy with the feed-back of energy being due to the location of the resistance in the electronic current path. Thus with the 40 resistance located in the output circuit, an increase in the filament current, which as known produces an increase in the feed-back of energy from the output to the input circuit due to an increase of the plate potential 45 or the electronic flow of current in the output circuit, produces a corresponding increase in the potential drop across the output resistance R , and hence a corresponding increase in the plate voltage which is in 50 phase with the grid voltage, resulting in an increase of abstraction or feed-forward of energy corresponding with the feed-back increase. Likewise the feed-forward and feed-back of energy will be equalized independent 55 of any variation of the plate potential or a change in the amplification constant of the tube or any changes in the grid-plate capacity of the tube resulting from replacement or substitution of tubes of different 60 types.

As heretofore mentioned, the prime object of the present invention relates to improvements in this method of controlling or neutralizing feed-back reactions in amplifier 65 systems by producing a compensating feed-

forward reaction, the improvements consisting primarily in the provision of means for controlling the energy output, amplification or volume of the system simultaneously with the control of the stabilization of the 70 system. More specifically, it is a desideratum of the present invention to simplify the control of tuned radio frequency systems 75 embodying feed-back neutralizing means in which unitary means may be employed for controlling the output volume of the system and the stabilizing of the circuits, making such control of stabilization furthermore substantially independent of the tube characteristics or constants. These 80 objects of the invention are accomplished by the provision of potentiometer means in the plate circuit of the tube, associated with the means for coupling the output circuit to a subsequent circuit so that adjustment of the potentiometer simultaneously 85 controls the output energy in the output circuit and the stabilization of the system.

Referring now to Fig. 1 of the drawings, the invention is shown applied to the second radio frequency stage, the output circuit o' being provided with the primary p^3 of the transformer T^3 , the said primary being inductively coupled to the transformer secondary s^3 of the next input circuit i^2 , and associated with the transformer primary p^3 I provide the potentiometer generally designated as P , which preferably comprises a resistance element 28 arranged across and preferably in shunt with the transformer primary p^3 and a movable contact element 29 connected to the positive terminal of the B battery by means of the conductors 30 and 31, the plate 12 of the tube a' being connected to the potentiometer-primary combination by means of the conductor 32.

As will be described more in detail hereinafter, movement of the contact 29 along the potentiometer resistance 28 has the effect of controlling the feed-back and feed-forward reactions and the selectivity of the amplifier system as a whole and of controlling the energy transmitted from the output circuit o' to the succeeding circuits, which in the embodiment of the invention exemplified in Fig. 1 of the drawings is the input circuit of the detecting tube a^2 .

Since the volume or energy output of the system is controlled by means of the potentiometer P , the usual filament current control is eliminated, the filament circuit f of the first radio frequency tube a being provided with the fixed resistance 20 aforementioned, and the filament circuits f' and f^2 of the remaining tubes being similarly 125 provided with fixed resistance elements 33 and 34, these filament circuits being connected, as usual, by means of the conductors 35 and 36 to the terminals of the battery A. By eliminating the usual filament current 130

controlling rheostats, not only is the number of control units in a receiving set reduced, but the secondary effects on the tuning of the system resulting from a change of filament current are avoided. This may be seen by reference to the first radio frequency stage of the system, as shown in Fig. 1 of the drawings. If the volume or the amplitude of the output energy were controlled by means of varying the filament current, the input circuit i would be detuned due to the variation of the effective capacity of the input circuit with a change of filament current. The control of the volume or energy output by the potentiometer P inhibits the production of such detuning effects, and such volume control is therefore accomplished along with a control of stabilization of the system without the disadvantages inherent in prior systems of this character.

The detecting stage embodying the tube a^2 may, if desired, be connected to one or more audio frequency amplifying stages, and for simplicity of illustration, the final output circuit embodying the sound responsive instruments such as the phones 37 is shown arranged in the output circuit o^2 of the detector stage. The input circuits i' and i^2 are of the tuned type, the former being provided with the tuning condenser 38, and the latter with the tuning condenser 39, the input circuit of the detecting stage being provided as usual with the integrating device or grid leak 40. Preferably there are provided the by-pass condensers 41 and 42.

Referring now to Fig. 2 of the drawings, I show a modification of the invention applied to a radio frequency system having two stages of radio frequency amplification and one stage of detection similar to the system shown in Fig. 1 of the drawings, similar parts being designated by similar reference characters. The system disclosed in Fig. 2 of the drawings differs from that shown in Fig. 1 by the provision of a potentiometer control means in the output circuits o and o' of both radio frequency stages, the output circuit o' of both radio frequency tube a being provided with the potentiometer P' , and the output circuit o' of the second radio frequency tube a^2 being provided with the potentiometer P^2 .

The potentiometer P' is similar to that heretofore described in connection with Fig. 1 of the drawings, having a resistance element 28 across and preferably in shunt with the transformer primary p^2 , and having a movable contact 29 connected by means of the conductor 30 to the positive side of the B battery, the potentiometer-primary combination being in turn connected to the plate 12 of the electron discharge device a by means of the conductor 32. The potentiometer P^2 for the second radio frequency tube a^2 has its movable contact connected

to the plate instead of the positive terminal of the B battery, and said potentiometer comprises a resistance element 28' in shunt with the transformer primary p^3 and a contact element 29' connected to the plate 12 of the tube a^2 by means of the conductor 32', the potentiometer-transformer combination being in turn connected at its lower junction point to the positive terminal of the B battery by means of the conductor 30'. Either of the potentiometer arrangements P' or P^2 may be employed, depending upon the engineering construction of the set. In the potentiometer P^2 , the movable contact is on the high potential side of the circuit, whereas in the potentiometer P' the movable contact is on the low potential side of the alternating current circuit. Both forms of the invention may be employed with equal success, the second form being preferred when the parts of the radio receiving set are properly shielded and the first form being desirable when the capacity between the primary and the secondary of the transformer is maintained low.

The function of the potentiometer control and the principles of the invention may be explained by reference to Fig. 3 of the drawings, which graphically shows the volume and stabilization control produced by a plate circuit potentiometer of the type associated with the second radio frequency stage a' of Fig. 2 of the drawings, this potentiometer P^2 comprising, as shown in Fig. 3 of the drawings, the resistance 28' in shunt with the transformer primary p^3 and the movable contact 29' connected to the plate 12, the potentiometer-primary combination being in turn connected at the lower junction point to the B plus battery terminal. Preferably the resistance 28' is about ten thousand ohms, and is equal to the output impedance of the output circuit or the filament plate impedance of the tube, the output impedance of the output circuit being made equal to the filament plate tube impedance.

The energy output or volume control is effected by movement of the potentiometer contact along the potentiometer resistance, the position of the potentiometer contact determining the distribution of alternating current flowing through the primary p^3 of the transformer. When the potentiometer contact such as 29' is at the lower junction point 45 of the potentiometer-primary combination, none of the plate current variations traverses the primary of the transformer, and hence the energy output is substantially zero; and as the potentiometer contact is moved from this position towards the upper junction point 46 of the potentiometer-primary combination, larger and larger fractions of the plate current variations traverse the primary coil, and this has the effect of increasing the coupling of the

transformer. This increase of coupling would of itself cause an increase of the output volume, were it not for the feed-back and feed-forward reactions which serve to 5 change the receptivity of the oscillating circuits. The control of the volume or energy output of the system by this movement of the potentiometer contact is depicted in the graph forming part of Fig. 3 of the drawings, by the volume curve 47, the characteristic operation of the volume control being that as the potentiometer contact is moved from the lower junction point to the upper junction point of the potentiometer-trans- 10 former combination, the volume increases rapidly and then is substantially constant around the mid-part of the potentiometer adjustment, and then again increases rapidly until a point X is reached, at which oscillations 15 are produced, such oscillations being obtained, as shown by the curve 48, as the potentiometer contact is moved from such point towards the upper junction point of the potentiometer. As will be pointed out herein- 20 below, the potentiometer control may be designed to vary the configuration of the volume curve to suit the needs or requirements of service, the structure having the characteristic of great flexibility; and it 25 will be seen from the foregoing that the energy output or volume of the system may be varied over a wide range, as for example from one to ten thousand, this being accom- 30 plished without altering the filament current of the amplifier tubes, the structure thus 35 affording a very flexible and long-range volume control.

The change of volume control by the potentiometer adjustment varies the feed-back 40 of energy from the output circuit to the input circuit, the feed-back increasing with the increasing change of volume due to the larger alternating potentials on the plate as the effective transformer coupling is in- 45 creased. This is depicted in the graph of Fig. 3 of the drawings by the curve 49 cal- 50 brated in terms of the negative feed-back resistance of the grid circuit produced by the feed-back of energy. It will be seen that as the potentiometer contact moves from the lower to the upper junction point of the potentiometer, the negative feed-back resistance increases from a minimum to a maximum value.

55 The function and principle of operation of the potentiometer adjustment for controlling the stabilization of the system, that is, the suitable control of the feed-back reactions so as to eliminate the oscillations and 60 obtain proper tone quality and the suitable control of the damping factor of the input circuit so as to get the right broadness of tuning or selectivity of the system, is also graphically depicted in Fig. 3 of the drawings, by means of the curve 50, which is cal-

ibrated in terms of the positive feed-forward resistance of the grid circuit produced by the potentiometer adjustment. By reference to Fig. 3, it will be seen that as the potentiometer contact is moved from the lower junction point to the upper junction point of the potentiometer, the feed-forward resistance, that is, the resistance which is in phase with the grid potential, increases from a value as shown by the curve 51, which is the circuit 70 ohmic resistance, to a maximum value which is reached when the potentiometer contact is substantially at the mid-point of the potentiometer resistance, the feed-forward resistance then decreasing from such maximum 75 value to that of the grid circuit ohmic resistance.

The inter-relation of the volume and stabilization controls by means of the potentiometer may be seen from the inter-reactions 80 of the curves 47-50, as shown in Fig. 3 of the drawings. The control regions may for the purpose of analysis be subdivided into the regions A, B, C and D. Considering first the feed-back and feed-forward curves 90 49 and 50, it will be seen that these intersect at a point X', the region between these curves to the left of the intersecting point corresponding to the effective damping resistance of the grid circuit, and hence to 95 the broadness of tuning of the same, this being represented for example by the ordinate 52; while the region between the curves to the right of the intersecting point X' corresponds to the intensity of self-generated 100 oscillations, the same being shown, for example, by the ordinate 53 at a given point of adjustment. As the potentiometer contact is moved down from the top junction point 46 of the potentiometer in the region 105 A, the self-generated oscillations become weaker, until the intersection or crossing point X' is reached, and at this point the oscillations cease, as shown by the intersection of the volume and oscillation curves 110 47 and 48. During this adjustment, it will be seen that the positive feed-forward resistance is gradually increased until the feed-forward resistance equals and hence neutralizes the feed-back resistance, the point of 115 neutralization corresponding to the point at which oscillations are eliminated. This region A is useful in the manipulation of the receiver when the receiver appears "dead" to determine whether or not the bat- 120 teries and tubes are faulty. Thus if no oscillations result as the potentiometer is moved into the region A, clear indication is had that the absence of signal is due either to run-down batteries or defective tubes. 125

The region A' forming part of the region of adjustment A is that between the maximum permissible selectivity and the maximum volume obtainable, and in this region the re-adjustments at maximum sensitivity 130

for distant-stage feed-back and atmospheric variations can be carried out. In a complete receiver, some adjustment is required to prevent the antenna or first input circuit from generating self-oscillations or from becoming greatly over-damped due either to distant stage feed-back variations, or due to variations of the antenna resistance resulting from variable atmospheric conditions. Where oscillation results from distant stage feed-back, the method of cutting down the amplification of the system to stop the oscillations usually results in a considerable loss of volume. With the present system, however, by adjusting the potentiometer in the region A', the small necessary changes in the damping of the input circuit can be effected so as to stop the disturbing oscillations without any substantial loss of volume.

The adjustment region B corresponds to approximately constant volume, as shown by the curve 47, with a variable selectivity or damping of the circuits as shown by the ordinates between the curves 49 and 50, the selectivity or damping being variable usually in the order of from .01 to .05 (log. dec.) in receivers having three tube circuits. In this region the feed-back and feed-forward resistances substantially balance, the change in their difference being the factor which causes the variation of selectivity. This range of operation is useful for pick-up work, since the receiver is broadly tuned and yet has the desired sensitivity.

The operating region C is one of variable volume and selectivity, marking a transition into the operating region D, in which latter the receiver has constant selectivity and variable volume. The region D is that in which the majority of reception is performed, as from stations up to fifty miles distance. In this region the receiver has a moderate selectivity corresponding substantially to the normal ohmic resistance of the circuits without any reaction components. In this region the volume is variable over an extremely wide range, namely, from zero signal on the strongest local stations up to approximately one-third of the maximum sensitivity of the receiver.

The particular configuration that the volume curve assumes is dependent upon a number of factors, such as the inter-relation of the feed-back and feed-forward curves and the design of the potentiometer resistance; and where, as shown in Fig. 3 of the drawings, the resistance is uniformly distributed in the potentiometer, to volume curve first rapidly increases with the potentiometer adjustment, and then increases more slightly until the constant value is reached, and thereafter increases again up to the point of oscillation.

The relatively slow increase of volume in

the region C is due to the oppositely working factors of increased transformer coupling and increased damping of the oscillatory circuit. The transformer coupling in this region is increasing quite rapidly, and would of itself produce a more rapid increase of volume, but this is in part negated by the slow increase of the resistance of the oscillating input circuit. In the operating region B approaching the region A', the volume increases slightly due primarily to the decrease of damping of the oscillatory input circuit as the feed-back and feed-forward reactions approach each other. In the region of A' adjacent to region B, further increases of volume may be obtained, but these are normally not useful, since in this region the selectivity of the set becomes so great as to introduce distortion of the audio tone quality due to the inability of the circuits to transmit the whole wave band corresponding to the modulated carrier wave, for as will be understood by those skilled in the art, when the resistance of the input circuit is very large, the circuit has high damping and is broadly tuned, and when this resistance is moderate, the circuit is more selective, and when the resistance is nearly zero, the circuit is super-selective, that is, it tunes so sharply that only part of the modulated wave band is received; and when the resistance is zero or less, the circuit tends to oscillate of its own accord.

One of the important problems in the proper design of a stabilizing control means is to so design and construct the control instrumentalities that all of the circuits will receive substantially the same changes in damping during adjustment. This is accomplished by the potentiometer system of my present invention, the damping or selectivity of all the circuits being changed in the same direction during the potentiometer adjustment. Thus, referring to Fig. 1 of the drawings, the variation of the potentiometer P serves to control the damping of the tuned circuits i and i' , and this occurs because if the resistance effective for feed-forward in the potentiometer be increased, the damping of the input circuit i' is increased, and an increase of damping in this circuit has the effect of reducing the impedance in the output circuit o of the first radio frequency tube, which in turn reduces the feed-back through such tube. Since the feed-forward through the first radio frequency tube is left constant, the input circuit i has a preponderance of feed-forward or energy loss, and therefore its damping is also increased. During the potentiometer adjustment, the third tuned circuit i'' sustains a corresponding increase of damping due to the fact that the plate resistance of the tube a' is connected more fully in parallel with the potentiometer resistance, tending to reduce the

resistance across the primary coil of the transformer T^3 , the reduction of this resistance causing the increase in the damping of the tuned circuit i^2 . The damping of all of the tuned circuits therefore is changed in the same direction with the potentiometer adjustment, and therefore the selectivity of the receiver as a whole, that is, of each adjustable tuning unit, is affected in the same direction. By means of the potentiometer of my invention, therefore, one circuit will not be over-damped in comparison with another circuit during the potentiometer adjustment, and the different circuits will receive substantially similar changes in the damping factor.

The potentiometer resistance may be designed depending upon the operating characteristics which are desired for the receiver. Referring again to Fig. 3 of the drawings, the operating range D is that of constant selectivity with variable volume, while the operating range B is conversely that of constant volume with variable selectivity. Where it is desired to control the selectivity without change in volume, the resistance of the potentiometer may be distributed to produce the curve shown in Fig. 3 of the drawings. The operating region A' is a critical region, and is of greater relative importance than the remainder of the operating region A, and this region A' may be made larger by suitable distribution of the potentiometer resistance. Since from a practical operating viewpoint the region D is more suitable than the region B, the potentiometer resistance as a whole may be varied to modify the volume and oscillation curve characteristics, as shown, for example, in Fig. 4 of the drawings.

Referring now to Fig. 4 of the drawings, a potentiometer P^3 is provided having a resistance 28^2 and a movable contact 29^2 , the said resistance being associated with a transformer primary p^4 . The potentiometer resistance is distributed, as graphically indicated in Fig. 4, so that the operating regions A—D produce the volume and oscillation curves 54 and 55 respectively, shown in the graph of Fig. 4. By re-adjusting the resistance in the region A, the critical operating region A', which may be considered as the super-selectivity and oscillation-control region, may be suitably lengthened, and the remainder of the region A, which is of relatively small utility, may be considerably decreased in range. Similarly, the region D, which is that of constant selectivity with variable volume, and the adjoining region C having variable volume and slightly variable selectivity, may be made to occupy more than fifty per cent of the potentiometer dial range, with the region B reduced to relatively small proportions.

The use and operation of the volume and

stabilization control system of my invention and the many advantages thereof will in the main be fully apparent from the detailed description thereof. It will be further apparent that numerous changes may be made in the arrangement and control elements of the potentiometer without departing from the spirit of the invention, defined in the following claims.

I claim:

1. A radio frequency amplifier comprising an electron discharge tube having a grid circuit, a plate circuit and a filament system, coupling means for coupling the plate circuit to a subsequent circuit and mechanism for controlling the feed-back reactions between the grid and plate of said tube comprising an impedance in the plate circuit in shunt with the plate circuit component of said coupling means, the plate electrode and the filament system being connected to selected tap points of said shunt impedance.

2. A radio frequency amplifier comprising an electron discharge tube having a grid circuit, a plate circuit and a filament system, a transformer coupling means for coupling the plate circuit to a subsequent circuit and mechanism for controlling the feed-back reactions between the grid and plate of said tube comprising a resistor impedance in the plate circuit in shunt with the primary of said transformer coupling means, the plate electrode and the filament system being connected to suitably tapped points of said shunt impedance.

3. A radio frequency amplifier comprising an electron discharge tube having a grid circuit, a plate circuit and a filament system, a tuned circuit, inductive coupling means for coupling the said plate circuit to the tuned circuit and mechanism for neutralizing the feed-back reactions via the grid and plate of said tube due to said coupling means and tuned circuit comprising an impedance in the plate circuit in shunt with the inductive plate circuit component of said coupling means, the plate electrode and the filament system being connected to selected tapped points of said shunt impedance.

4. A radio frequency amplifier system comprising an electron discharge tube having a grid circuit, a plate circuit and a filament system, inductive coupling means for coupling said plate circuit to a subsequent circuit, and mechanism for simultaneously fixing the degree of coupling of said coupling means and the feed-back reaction across the grid and plate electrodes, said mechanism comprising an impedance in the said plate circuit in shunt with the plate circuit component of said coupling means, and connections between said plate electrode and filament system with tapped points on said shunt impedance.

5. A radio frequency amplifier system comprising an electron discharge tube having a grid circuit, a plate circuit and a filament system, a tuned circuit, transformer coupling means for coupling said plate circuit to said tuned circuit, and mechanism for simultaneously fixing the degree of coupling of said coupling means and the feed-back reaction across the grid and plate electrodes, said mechanism comprising a resistor impedance in the said plate circuit in shunt with the primary of said transformer coupling means, and connections between said plate electrode and filament system with selected tapped points on said shunt impedance.

6. A radio frequency amplifier system comprising an electron discharge tube having a grid circuit, a plate circuit and a filament system, coupling means for coupling said plate circuit to a subsequent circuit, and mechanism for simultaneously fixing the degree of coupling of said coupling means and the feed-back reaction across the grid and plate electrodes, said mechanism comprising an impedance in the said plate circuit in shunt with the plate circuit component of said coupling means, and connections between said plate electrode and filament system with selected points on said shunt impedance, the coupling means and said impedance having constants for producing an effective feed-forward resistance in said plate circuit balancing the feed-back resistance component which is due to the inductive reactance of said coupled circuits.

7. A radio frequency amplifier system comprising an electron discharge tube having a grid circuit, a plate circuit and a filament system, a tuned circuit, transformer coupling means for coupling said plate circuit to said tuned circuit, and mechanism for simultaneously fixing the degree of coupling of said coupling means and the feed-back reaction across the grid and plate electrodes, said mechanism comprising a resistor impedance in the said plate circuit in shunt with the primary of said transformer coupling means, and connections between said plate electrode and filament system with suitable points on said shunt impedance, the transformer coupling means and said impedance having constants for producing an effective feed-forward resistance in said plate circuit balancing the feed-back resistance component which is due to the inductive reactance of said coupled circuits.

8. A radio frequency amplifier comprising an electron discharge tube having a filament, a grid and a plate, a plate circuit including a coupling means for coupling to a succeeding circuit, and mechanism for controlling the feed-back reactions between the grid and plate of said tube comprising an impedance connected across said coupling

means to form therewith a shunt circuit having two branches, and connections from the plate and filament of the tube to said shunt circuit, said connections being made to points in the shunt circuit so that components of both the coupling means and impedance are included in at least one branch of said shunt circuit.

9. A radio frequency amplifier comprising an electron discharge tube having a filament, a grid and a plate, a tuned circuit, a plate circuit including a coupling means for coupling said plate circuit to the tuned circuit, and mechanism for controlling the feed-back reactions between the grid and plate of said tube comprising an impedance connected across said coupling means to form therewith a shunt circuit having two branches, and connections from the plate and filament of the tube to said shunt circuit, said connections being made to points in the shunt circuit so that components of both the coupling means and impedance are included in at least one branch of said shunt circuit.

10. A radio frequency amplifier comprising an electron discharge tube having a grid circuit, a plate circuit and a filament system, a coupling transformer having its primary in the plate circuit and having a tuned secondary, and means for controlling the feed-back reactions between the grid and plate of said tube comprising a potentiometer in the said plate circuit in shunt with said transformer primary and connections between the plate and filament of the tube with said potentiometer, said connections being adjustable to simultaneously vary the in series resistance of the plate circuit and the alternating current potential across the transformer primary.

11. An amplifying system comprising a three electrode tube embodying a filament, a grid and a plate, a grid circuit, a plate circuit, a coupling transformer having its primary in the plate circuit, and a high resistance potentiometer connected across said transformer primary, the potentiometer resistance being of the order of magnitude of the filament-plate-impedance of the tube.

12. An amplifying system comprising a three electrode tube embodying a filament, a grid and a plate, a grid circuit, a plate circuit, a coupling transformer having its primary in the plate circuit, and a high resistance potentiometer connected across said transformer primary, the potentiometer resistance being substantially equal to the filament-plate-impedance of the tube, the same being equal to the output impedance of the plate circuit.

Signed at New York city, in the county of New York and State of New York, this 6th day of July, A. D. 1925.

LESTER L. JONES.
